[57] CLAIM

The ornamental design for a waist-mounted ball paddle, as shown and described.

DESCRIPTION

FIG. 1 is a perspective view of a first embodiment of a waist-mounted ball paddle showing my new design;

FIG. 2 is a top plan view thereof;

FIG. 3 is a side elevational view thereof;

FIG. 4 is a front elevational view thereof;

FIG. 5 is a rear elevational view thereof;

FIG. 6 is a top plan view of a waist-mounted ball paddle showing a second embodiment of my new design;

FIGS. 3, 4 and 5 illustrate side, front, and rear elevational views, respectively, of the second embodiment of my new design illustrated in FIG. 6;

FIG. 7 is a top plan view of a waist-mounted ball paddle showing a third embodiment of my new design;

FIG. 8 is a side elevational view thereof;

FIG. 9 is a front elevational view thereof;

FIG. 10 is a rear elevational view thereof.
